INTERNAL COMBUSTION ENGINE CYLINDER ASSEMBLIES

Marsden Ware, Huntington Woods, and Julius E. Witzky, Royal Oak, Mich., assignors to Studebaker-Packard Corporation, a corporation of Michigan

Application February 2, 1951, Serial No. 209,109

8 Claims. (Cl. 123—41.31)

This invention relates to internal combustion engines and particularly to internal combustion engine cylinder assemblies of the type including means defining a combustion space and a space immediately adjacent the combustion space through which a stream of cooling water may be continually passed.

In the construction of internal combustion engines, particularly engines of the larger type such as diesel engines, it is sometimes found desirable to separately form the several cylinder assemblies and to separately assemble such assemblies in desired relationship on the cylinder block. It is also generally preferred to form each such assembly by permanently uniting a cylinder barrel fabricated by a forging operation to a water space defining structure which is either built of separately formed parts united by welding or which is formed by a casting operation, since each of these parts may then be given the physical characteristics calculated to enable it to most efficiently perform its functions over a long period of time while, at the same time, the full benefits of an integral structure are realized.

In accordance with the present invention an improved cylinder barrel and head assembly is provided, having material advantages over generally similar structures heretofore designed or suggested. One feature of the invention is the improved means forming portion of this assembly and which defines the space through which cooling water is circulated. The common wall between the combustion space of the assembly and the water space immediately above it is, of course, subjected, in the operation of the engine in which the assembly may be incorporated, to the action of very high temperature gases and also to the rapidly repeated blows resulting from the explosions which occur in the cylinder. The upper end of the cylinder, and especially this common dividing wall between combustion and water spaces, must, therefore, be given strong mechanical support and must be maintained sufficiently cool to prevent the development of structural weaknesses when the engine is in use.

This invention provides a cylinder and cylinder head assembly in which the wall which divides the combustion and cooling water spaces is both cooled in a novel and improved manner and is mechanically supported from above in such a way that its resistance to repeated explosions in the cylinder below is all that could be desired. These advantages are realized in a structure of minimum weight, weight being conserved by providing bridging webs so located that the entire member is truss-like in form.

The present invention is particularly related to that type of engine embodying a small pre-combustion chamber formed in the cylinder head and means are provided whereby the wall of this pre-combustion chamber may be adequately cooled. This is done by bringing the water up from the cylinder cooling jacket through a substantially complete annular series of openings adjacent the periphery of the cylinder head and directing all of this water radially inward across the top of the head wall

2

of the cylinder head and against the outer wall of the pre-combustion chamber.

The improved cylinder assembly is disclosed in the accompanying drawings, one preferred embodiment being illustrated by way of example. It will be appreciated that minor departures may be made in adapting the invention to internal combustion engine cylinder assemblies which vary in dimension and other minor aspects, resulting in variations in engine horse power, all without departure from the teachings of the invention.

In the drawings:

Figure 1 is a transverse section through a portion of an internal combustion engine, the section being taken through the longitudinal axis of one of the novel cylinder assemblies;

Figure 2 is a section taken through the axis of the cylinder assembly in such manner as to show an inlet and an exhaust valve, with the ports which they control respectively, being taken on the line 2—2 of Figure 3;

Figure 3 is a section on line 3—3 of Figure 2, no portion of the cylinder block being shown;

Figure 4 is a section on line 4—4 of Figure 1, the cylinder block being omitted; and

Figure 5 is a top plan view of portion of an internal combustion engine cylinder block, showing two of the offtakes for leading cooling water from the water cooling spaces of adjacent cylinder assemblies to the manifold provided for the removal of cooling water from all of the cylinders.

Details of the engine block 10 to which the improved cylinder assembly is to be applied may, of course, vary widely and no attempt has been made to illustrate such a block in full. It may be said that the block is provided with the usual cylindrical bores for the reception of the cylinder assemblies. Each such assembly comprises essentially a cylinder barrel 11, a cylinder head 12, and means 14 for retaining a shoulder of the cylinder barrel and head in the engine block 10, a shoulder of the cylinder barrel bearing against a shoulder of the cylinder block.

This novel retaining means is of the type disclosed in co-pending application Serial No. 179,493 to Julius E. Witzky, filed August 15, 1950, now Patent No. 2,654,357, issued October 6, 1953.

That portion 13 of the engine block which surrounds the cylinder barrel 11 forms a water jacket 16. The space just below the cylinder head inside the cylinder barrel may be referred to as the main combustion chamber.

The cylinder barrel 11 and the head 12 may be cast or forged separately and welded together. Thus they may be formed as disclosed in co-pending application Serial No. 157,762 to R. E. Van Deventer, filed April 24, 1950, now abandoned.

Prior to assembly of the cast member 12 and the barrel 11 a circular series of apertures 15 are formed in the cast member, these apertures or ducts being either formed as an incident of the casting operation or by drilling after casting. The ducts 15 are distributed largely as shown in Figure 3 and are of such size, when taken together, as to ensure the passage into the water space 12a, of a supply of cooling water quite adequate for all needs during the operation of the engine in which the assembly is used. As shown in the drawings, the lower ends of all of the ports 15 are in open communication with the water space 16, intermediate the cylinder barrel 11 and that portion of the cylinder block 10 which immediately envelopes the cylinder barrel. The horizontally disposed partition or wall 18 of the cylinder head divides the main combustion space of the engine from the cooling water space of the cylinder head. Disposed above wall 18 a relatively short distance, and generally parallel to the upper surface of this wall, are several webs 19 in the nature of baffles which direct the inflowing

streams of cooling water issuing from ports 15 toward the axis of the assembly, causing the cooling water to flow through the chamber C across the upper surface of the dividing wall 18 and against the wall 20 of the pre-combustion chamber 20a. Each chamber C narrows 5 gradually toward the discharge port C', through which discharge port water from a substantial number of inlet ports 15 must pass and, as a result of this gradual contraction of the water channel the cooling water passes through port C' at increased velocity into the chamber 10 above. The rate at which heat is removed from the wall of the pre-combustion chamber, by causing the cooling water to directly impinge against that wall and thereafter flow rapidly upwardly along the wall surface of the chamber, is substantially increased, the water 15 stream rapidly scrubbing away, so to speak, the heat imparted to the wall by the combustion within the chamber. There is thus conducted away from these walls a sufficient amount of the heat imparted thereto by the burning gases to maintain the wall at a desired 20 temperature.

The cylinder assembly selected for disclosure is designed in such manner that the fuel will be initially supplied to and burned within the pre-combustion chamber 20a and the wall of such a pre-combustion chamber, which is generally spherical, is indicated at 20. The webs 19, it will be observed, have upturned portions 19a spaced from the outer surfaces of the wall of the pre-combustion chamber so that the upwardly flowing streams 25 of cooling water sweep over the outer wall surfaces of the pre-combustion chamber before entering the larger space 12a above the webs or baffles 19. The pre-combustion chamber is supplied from above with fuel by means of a fuel injector 22 which is positioned in an upwardly tapering socket provided for its reception and 30 the gases resulting from combustion in the pre-combustion chamber pass downwardly into the cylinder below through a burner 23. The usual glow plug or ignition device 24 is provided and is threaded into a generally horizontally disposed passage formed in the cast member 12 and the 35 inner end of which is in communication with the pre-combustion chamber.

It will be appreciated that provision is made for valves, valve guides and ports through which combustion supporting air may enter the cylinder and products of combustion escape. Two inlet valves and two outlet valves are provided, there being two ports in the wall 18 for the introduction of air and two ports in that wall for the escape of products of combustion. The inlet valves V, of which one is shown in side elevation in Figure 2, are 40 provided with stems 26 and 27, respectively, and the exhaust valves, one of which is indicated at V' in Figure 2, are provided with hollow stems 28 and 29. Valve guides are indicated at 30 and 31, respectively, in Figure 2, and each of these sleeve-like members is housed within 45 a tubular element which forms an integral portion of the cast member 12, these elements being indicated at 32, 33, 34 and 35 (in Figure 3), the annular upper end surfaces 50 of the four valve guides and the four guide supporting elements lying within or adjacent a common plane, as 55 shown in Figure 2.

The annular upper end surface of the central tubular part 12b, which receives the injector nozzle is likewise disposed in the same plane, which plane is a slight distance above the bevelled upper edge of the cylindrical shell of cast member 12. The upper end of the water space defined by this member is closed by a circular plate 60 65 36, the bevelled periphery of this plate being attached to the bevelled upper edge of the cylindrical wall of casting 12 by a welding operation, the weld metal being indicated at 37. Apertures are provided in plate 36 through which the cylindrical upper end of the tubular injection nozzle receiving part 12b projects, as shown in Figure 1, and the upper annular edges of the cylindrical elements 32, 33, 34 and 35, which house the four valve guides, also 70

project through apertures in plate 36 provided for that purpose. The edges of the apertures thus provided in plate 36 are bevelled, as shown in Figure 2, to facilitate welding and, encircling each of the tubular parts just mentioned, and sealing and securing the upper end of each to plate 36, are bands of weld material, indicated at 38, 39 and 40 in Figure 2, the space 12a contained within the casting 12 and provided for the reception of cooling water being thus sealed off at its top and the cooling water chamber being thus rendered water-tight. A further aperture 42 formed in the plate 36 constitutes a port for the escape of cooling water, water passing upwardly through this port entering the lower end of a tubular duct 43 firmly attached to the plate by one or more bolts such as indicated at 44.

The discharge port of the offtake duct 43 is in register with a port 46 formed in the wall of an offtake manifold 47 into which the cooling water from a number of cylinders may pass and by which such water, which has become relatively warm in passing through the water cooling space of the cylinder assembly, may be conducted to a cooling means prior to recirculation.

For the purpose of rigidly supporting the wall 18, which is subjected to the heavy, repeated and sudden pressures of the exploding charges in the engine, a circular series of webs 50 are provided, four such webs being utilized in the form of the cylinder assembly shown. These webs are radially disposed, as may be seen from an inspection of Figure 4, and are essentially triangular, the relatively long base of each web being cast integral with the dividing wall 18 and the outer edge being cast integral with the cylindrical wall. These webs transmit forces applied to wall 18 to the cylindrical wall, which is closely backed by the cylinder block 10, and hence the applied forces are widely distributed and the wall 18 rigidly supported. The reinforcing webs 50 do not interfere with the upward flow of the cooling water. To facilitate casting of the head 12 the channels C, intermediate webs 19 and dividing wall 18, into which water passing upwardly through the circular series of ports 15 pass, and which empty into the upwardly directed channels or ports C' previously referred to, are left open at their outer ends and, as a final step in the completion of the assembly, these ends are closed by means of a circular band 52, secured in position by welds 53 and 54.

It will be understood that any suitable valve operating mechanism may be employed, that illustrated by way of example including the telescoping valve spring housings 56, cam shafts 57, and cams 58, and that other parts of the engine and cylinder block, not specifically referred to, may be of conventional design.

Having thus described the invention, what is claimed as new and desired to be secured by Letters Patent is:

1. An internal combustion engine cylinder assembly comprising coaxial barrel and head portions and having a common wall disposed transversely to their common axis, means defining with said common wall a chamber for a cooling fluid, a pre-combustion chamber centrally positioned within the cooling fluid chamber and integral with said common wall, the said means having fluid inlet and outlet ports and baffles whereby fluid entering the chamber is caused to flow inwardly toward said pre-combustion chamber and then upwardly away from said common wall.

2. An internal combustion engine cylinder assembly comprising a wall to separate the combustion and water spaces of such assembly, coaxial cylinders of unequal diameter integral with said wall, thus providing an annular shoulder of substantial cross section, said shoulder having formed therein a circular series of water inlet ducts through which water may be passed to cool said shoulder and the outer margin of the dividing wall.

3. An internal combustion engine cylinder assembly

comprising a water jacketed cylinder barrel, a cylinder head for said barrel, said head having a central pre-combustion chamber communicating with the interior of the cylinder barrel and having a cooling chamber formed around said pre-combustion chamber, means defining a circular series of cooling fluid channels adjacent the periphery of said head, said channels extending from the cylinder water jacket to the water jacket of the head, means receiving the cooling fluid entering said head from said fluid channels and forming therefrom a plurality of streams which pass upwardly in contact with the walls of said pre-combustion chamber, each such stream being closely confined laterally in the vicinity of the pre-combustion chamber, and outlet means for said cooling fluid.

4. An internal combustion engine cylinder assembly comprising a water jacketed cylinder barrel, a cylinder head for said barrel, said head having a central pre-combustion chamber communicating with the interior of the cylinder barrel and having a cooling chamber formed around said pre-combustion chamber, means defining a circular series of cooling fluid channels adjacent the periphery of said head, said channels extending from the cylinder water jacket to the water jacket of the head, means directing the cooling fluid from said channels in a series of streams of gradually narrowing cross section radially inward across the head wall of said cylinder head to upwardly opening ports of discharge formed in part by the wall of said pre-combustion chamber, and outlet means for said cooling fluid.

5. An internal combustion engine cylinder assembly comprising coaxial barrel and head portions and having a common wall disposed transversely to their common axis, means defining with said common wall a chamber for a cooling fluid, said chamber having fluid inlet ports adjacent the periphery of said common wall and a fluid outlet port communicating therewith, and baffle means generally parallel with said common wall within said chamber for directing inflowing streams of fluid toward the axis of the assembly, said streams of fluid thereby sweeping over the surface of said common wall before moving into said chamber and thence to said outlet port, said chamber defining means including a wall which defines a pre-combustion chamber positioned centrally in the cooling fluid chamber and said baffle means being positioned to direct fluid against the said pre-combustion chamber wall.

6. An internal combustion engine cylinder assembly comprising coaxial barrel and head portions and having a common wall disposed transversely to their common axis, means integral with said head and barrel portions for defining with said common wall a chamber for a cooling fluid, said means including a cylindrical outer wall centered on said common axis, and a plurality of strengthening webs disposed radially of said axis and having a generally fluid tight and supporting engagement

with said common wall and cylindrical outer wall, said webs being generally triangular in radial section, becoming smaller as the distance from said common wall increases.

5 7. An internal combustion engine cylinder assembly comprising coaxial barrel and head portions and having a common wall disposed transversely to their common axis, means defining with said common wall a chamber for a cooling fluid, said chamber having a circular series of fluid inlet ports adjacent the periphery of said common wall and a fluid outlet port communicating therewith, and baffle means generally parallel with said common wall within said chamber for directing inflowing streams of fluid from said inlet ports toward the axis of the assembly, said streams of fluid thereby sweeping over the surface of said common wall before moving into said chamber and thence to said outlet port, and a plurality of strengthening webs disposed radially of said axis and having a generally fluid tight and supporting engagement with said common wall and said baffle means, said webs becoming smaller as the distance from said common wall increases.

20 8. An internal combustion engine cylinder assembly comprising coaxial barrel and head portions formed as an integral structure, said structure having a common wall transverse to said axis which constitutes the upper end of the combustion space and the bottom of a cooling fluid chamber, said wall having four ports formed therein through which gases may pass, a gas duct leading from each port, said head portion including means defining 25 with said wall a chamber for cooling fluid, said means including a cylindrical outer wall integral at one end with said common wall and having four ports formed therein, one of said gas ducts connecting each port of the common wall to a port in the cylindrical wall respectively, 30 and said means including also a closure plate spaced somewhat from and disposed generally parallel to said common wall, the other end of said cylindrical wall and the periphery of said plate being joined to form an integral unit, the said chamber having a circular series of 35 ports therein, including ports directly below said ducts, for introducing cooling fluid through said common wall, and a port for permitting the escape of cooling fluid 40 through said closure plate.
